(57) **CLAIM**

The ornamental design for the cutlery implement, as shown and described.

DESCRIPTION

FIG. 1 is a perspective rear and left side view of the cutlery implement showing the new design;

FIG. 2 is a left side elevation view of the cutlery implement of FIG. 1; the right side view being identical;

FIG. 3 is a top plan view of the cutlery implement of FIG. 1;

FIG. 4 is a bottom plan view of the cutlery implement of FIG. 1;

FIG. 5 is a front elevation view of the cutlery implement of FIG. 1; and,

FIG. 6 is a rear elevation view of the cutlery implement of FIG. 1.

The ornamental design which is claimed is shown in solid lines in the drawings. The broken lines in the drawings are for illustrative purposes only and form no part of the claimed design.
